(57)

CLAIM

The ornamental design for a platform for electric vehicle as shown and described.

DESCRIPTION

FIG. 1 is a top, front, and right side perspective view of a platform for electric vehicle showing our new, original, and ornamental design;

FIG. 2 is a top plan view thereof;

FIG. 3 is a right side elevation view thereof; and,

FIG. 4 is a front elevation view thereof.

The broken line showing of certain structures in the drawings is for the purpose of illustrating optional features and forms no part of the claimed design.
